CHARLES ALGERNON PARSONS, STANLEY SMITH COOK, AND LOUIS MORTIMER DOUGLAS, OF NEWCASTLE-UPON-TYNE, ENGLAND; SAID COOK AND SAID DOUGLAS ASSIGNEES TO SAID PARSONS.

GEARED-TURBINE SYSTEM.

1,377,851.

Specification of Letters Patent. Patented May 10, 1921.

Original application filed October 31, 1918, Serial No. 260,552. Divided and this application filed August 11, 1919. Serial No. 316,921.

To all whom it may concern:

Be it known that we, CHARLES ALGERNON PARSONS, STANLEY SMITH COOK, and LOUIS MORTIMER DOUGLAS, all subjects of the King of Great Britain and Ireland, all residing at Heaton Works, Newcastle-upon-Tyne, in the county of Northumberland, England, have invented certain new and useful Improvements in Geared-Turbine Systems, of 10 which the following is a specification.

The present invention relates to geared turbine systems, in which a turbine transmits power through a double helical gear train.

15 As usually constructed turbines are provided with a thrust or adjusting block of the pivoted or ordinary type for the purpose of retaining the longitudinal position of the rotor relative to the stator. When 20 such a turbine is driving a pinion having double helical gear teeth, it is necessary to provide a sliding coupling between the pinion and the turbine rotor, in order that each may take up its own longitudinal position, 25 that of the turbine rotor being controlled by the adjusting block and that of the pinion by the intermeshing gear teeth.

30 Thrust blocks of the ordinary fixed collar type are frequently the cause of considerable trouble in operation, and pivoted thrust blocks, although they are practically free from running troubles if properly constructed, are somewhat expensive to manufacture. It is, therefore, desirable to dispense with adjusting blocks so far as is possible.

35 Sliding couplings have both the above mentioned disadvantages—they are very expensive to manufacture for high power, high 40 speed shafts and they are frequently the cause of considerable trouble in running.

The object of the present invention is to overcome these difficulties.

45 The invention consists in a geared turbine system in attaching the turbine rotor directly to the pinion shaft with a fixed coupling and causing the pressure per unit length of both of the intermeshing double helical pinions to be uniform.

50 The invention further consists in increasing the length of one of the helices of the

double helical pinions relatively to the other so as to balance the thrust exerted by the turbine and insure a substantially uniform distribution of pressure across the pinion 55 teeth.

The invention also consists in designing the turbine in such a manner that the difference in width of the helices required to balance the end thrust is that which will 60 cause the best distribution of forces possible, so far as deflection due to torque of the pinions is concerned.

The invention also consists in the improved geared turbine arrangements herein- 65 after described.

Referring to the accompanying drawings:—

Figure 1 shows the application of the invention to an impulse reaction turbine. 70

Fig. 2 is a diagram illustrating the most desirable proportion of the gearing.

Fig. 3 illustrates the application of the invention to a low pressure unbalanced turbine; and 75

Fig. 4 illustrates its application to double reduction gearing.

The invention is applicable to a geared turbine system employing any kind of turbine in which there is an axial thrust along 80 the shaft.

In the form of the invention illustrated in Fig. 1, an impulse-reaction turbine *r s* is employed in which the low pressure reaction portion *s* is unbalanced and the turbine consequently has an axial thrust in the direction of the pinion. In order to obtain as far as possible a uniform distribution of pressure across the pinion teeth, one of the helices *c* of the gear is made wider than the other *d*. This increased length of one of the helices is necessary in view of the fact that the torque transmitted by each of two equal and oppositely inclined helices is proportional to the longitudinal forces between 90 the teeth and the difference between the longitudinal forces in this case will be equal to the turbine thrust. With gears so proportioned, an added advantage is obtained from the fact that the deflections of the pinion due to its torque are more nearly equal 95 on the two helices of the pinion, when the 100

shorter helix is at the driving end. The turbine can be so designed, in fact, that its end thrust necessitates a difference in width of the helices which will cause the best possible distribution of the pressure on the teeth so far as the deflection due to torque of the pinions is concerned; that is the total deflections across the helices are equal.

This effect is illustrated in Fig. 2, in which assuming that the drive is from the left hand end and that the pressure on the teeth per unit of length is uniform, the ordinates of the curve represent torsional deflection or twist at points along the pinion. It is desirable that the maximum twist on each helix should be made as low as possible, and the lengths e_1, e_2 of the helices are therefore so chosen that the deflections d_1, d_2 are equal. This inequality of helix width results in an end thrust which is arranged to be balanced by that of the turbine.

Fig. 3 illustrates the modification in which a low pressure unbalanced turbine t with unequal helices c and d is employed.

As in the previous case, an astern turbine u is incorporated with the main turbine and the thrust of the main turbine is of such a direction and magnitude that it is balanced by the thrust produced by the unequal helical gear wheels when power is being transmitted through them.

Fig. 4 shows a double reduction gear in which both primary gears 20, 21, 22, 23, and secondary gears 24, 25, 26, 27, have the complementary helices of unequal widths, so that the steam thrust of the turbine 28 is carried by the gears with approximately uniform distribution of pressure on the teeth of the latter. The proportionate difference between the widths of the primary gears 20, 21, is much greater than that between the widths of the secondary gears 24, 25, on account of the relatively smaller total force on the teeth of the former.

In this installation, and all those in which the gears receive axial thrust from the turbine, the arrangement is preferably, but not necessarily, such that the turbine thrust is opposed to the propeller thrust.

It will be seen that in cases in which the turbine is to be exactly steam balanced and also in cases in which the unbalanced thrust is to be a determined quantity to suit the gear proportions adopted, means may be adopted for adjusting exactly the steam balance or thrust after the construction of the turbines. These means of adjustment should be permanent and may consist, in the case of a dummy piston, in connecting

the leak-off chamber behind the piston to a suitable stage of the turbine system which will give a back pressure insuring correct balance or thrust. As an alternative, the area of the dummy leakage escape passage may be adjusted, or the blades may be slightly opened or closed or partly baffled by a covering plate.

Though a fixed rigid flanged coupling is mentioned and shown on the drawings any coupling may be used which gives longitudinal and angular rigidity between the two elements.

Having now described our invention, what we claim as new and desire to secure by Letters Patent is:—

1. In a geared turbine system, a rotor, a shaft co-axial with the rotor and connected to it by a rigid coupling, a double helical pinion mounted on said shaft, the oppositely inclined parts of said pinion being of unequal length whereby the pressure per unit length of tooth of the intermeshing double helical pinion will be uniform, substantially as described.

2. In a geared turbine system a rotor, a shaft coaxial with the rotor and connected to it by a rigid coupling, a double helical pinion mounted on said shaft, the oppositely inclined parts of said pinion being of unequal length whereby the longitudinal thrust of the turbine rotor is balanced by an equal and opposite longitudinal thrust of the double helical pinion when power is being transmitted through said pinion, substantially as described.

3. In a geared turbine system as set forth in claim 2, a double helical pinion divided into parts having oppositely inclined teeth and of such a length that when power is transmitted through said pinion the total torsional deflections across the helices are equal.

4. In a geared turbine system as set forth in claim 1, primary gears meshing with the double helical pinion, and of a width corresponding to that of the parts of said double helical pinion with which they mesh and secondary gearing associated with each of the primary gears, said secondary gearing including members coaxial with the primary gears and having complementary helices of unequal widths, substantially as described.

In testimony whereof we have signed our names to this specification.

CHARLES ALGERNON PARSONS.

STANLEY SMITH COOK.

LOUIS MORTIMER DOUGLAS.
